UNITED STATES PATENT OFFICE

WILLIAM PRELLWITZ, OF PHILLIPSBURG, NEW JERSEY, ASSIGNOR TO
INGERSOLL-RAND COMPANY, OF NEW YORK, N. Y., A CORPORATION
OF NEW JERSEY.

HAMMER-DRILL.

No. 818,638.

Specification of Letters Patent.

Patented April 24, 1906.

Application filed December 7, 1905. Serial No. 290,690.

To all whom it may concern:

Be it known that I, WILLIAM PRELLWITZ, a citizen of the United States, and a resident of Phillipsburg, in the county of Warren and State of New Jersey, have invented a new and useful Improvement in Hammer-Drills, of which the following is a specification.

My invention relates to hammer-drills, and particularly to a hammer-drill having an air-feed and hand rotation.

In drills of this character it has been usual to fit the hammer-cylinder to the bore of its protective casing, leaving the space in front of the cylinder open to the external air and opening the space back of the cylinder to the air-inlet.

It has been found that when the casing is clamped in position on a column or support the walls of the casing are distorted sufficiently to prevent the ready forward feed of the tool-cylinder within the casing, owing to the pressure of air back of the same, and, in fact, the casing is frequently so much distorted as to absolutely prevent the forward feed of the said hammer-cylinder.

The objects of my invention are to provide certain improvements in the construction, form, and arrangement of the several parts whereby the walls of the protective casing are entirely spaced from the tool-cylinder, the tool-cylinder being supported from the ends of the casing and the entire space within the casing being opened to the air-feed, the forward feed of the tool-cylinder being insured by the excess of pressure back of the same, owing to the fact that the tail-rod of the cylinder is of less diameter than the cylinder itself. This arrangement prevents all danger of the tool-cylinder sticking in the protective casing, and thereby interfering with its forward feed.

A further object is to provide a structure of the above character in which the exhaust from the piston-chamber is led through the cylinder to a point exterior to the protective casing and through the tail-rod to a point exterior to the casing.

In the accompanying drawings, Figure 1 is a view of the hammer-drill in side elevation, a portion of the protective casing being broken away to more clearly show the position of the tool-cylinder therein; and Fig. 2 is a longitudinal central section through the drill.

The tool-cylinder is denoted by 1. To this cylinder is screwed a head-block 2, in which is located the usual valve-box 3 of any well-known or approved form, the holes 4 being formed in the head-block 2 for the admission of air to the valve-box. The contracted portion of the cylinder is provided with the usual hammer-piston chamber 5, in which the hammer-piston 6 is fitted to reciprocate.

The drill-tool is denoted by 7, and it is held in the usual bushing 8 at the forward end of the cylinder 1 in position to be struck by the hammer-piston 6.

A hollow tail-rod 9 extends rearwardly from the head-block 2 of the tool-cylinder 1, which tail-rod is provided at its rear end with the usual operating-handle 10, arranged to rotate the drill. A hollow protective casing has its cylindrical walls 11 entirely spaced from the cylinder 1, which casing is provided at its ends 12 and 13 with packed bearings 14 and 15, the tail-rod 9 being supported by and fitted to slide in the bearing 14 at the end 12 of the casing and the cylinder being supported by and fitted to slide in the bearing 15 at the end 13 of the casing.

An air-supply inlet 16 is located in the rear end 12 of the protective casing in position to permit a supply of the motive fluid to enter the interior of the casing and to pass through the walls 4 into position to be directed from the valve-box 3 to the front or back of the hammer-piston 6 in the usual manner.

An exhaust-port 17 leads from the chamber 5 in front of the hammer-piston 6 through the side walls of the cylinder 1 to a point exterior to the casing. In the present instance the exhaust-port 17 opens through the end of the cylinder at one side of the bushing 8.

The exhaust-port 18 for the chamber 5 in back of the hammer-piston leads through the tail-rod 9 to a point exterior to the protective casing—in the present instance through an annular series of holes 19 adjacent to the handle 10 at the rear end of the tail-rod. To direct the exhaust away from the operator from this last-named exhaust-port, I provide a deflector 20, which surrounds the annular series of holes 19, which deflector in the present instance is shown as forming an integral part of the handle 10.

By the construction herein shown and described it will be seen that the protective casing may be firmly clamped in position with-

out interfering with the forward feed of the cylinder, for the reason that any slight distortion in the casing will not affect the cylinder, as it is entirely supported by the ends of 5 the casing.

What I claim is—

1. In a hammer-drill, a hammer-cylinder and a hollow protective casing therefor having its walls entirely spaced from the cylinder, 10 the cylinder being supported only by the ends of the casing for the purpose set forth.

2. In a hammer-drill, a hammer-cylinder, its tail-rod and a protective casing having its walls entirely spaced from the cylinder, the 15 cylinder and tail-rod having sliding engagements with and supported only by the ends of the casing for the purpose set forth.

3. In a hammer-drill, a hammer-cylinder, its tail-rod of less diameter than the cylinder 20 and a protective casing having its walls entirely spaced from the cylinder, the cylinder and tail-rod having sliding engagements with and supported only by the ends of the casing for the purpose set forth.

25 4. In a hammer-drill, a hammer-cylinder, its tail-rod and a protective casing for the cylinder, the cylinder having an exhaust-port leading through the tail-rod to a point exterior to the casing.

30 5. In a hammer-drill, a hammer-cylinder, its tail-rod and a protective casing for the cylinder, the cylinder having one exhaust-port leading therethrough to a point exterior to the casing and another exhaust-port leading 35 through the tail-rod to a point exterior to the casing.

6. In a hammer-drill, a hammer-cylinder, its tail-rod, a protective casing for the cylinder, the cylinder having an exhaust-port 40 leading through the tail-rod to a point exterior to the casing and a deflector on the tail-rod for directing the exhaust away from the operator.

7. In a hammer-drill, a hammer-cylinder, 45 its tail-rod, a protective casing for the cylinder, the cylinder having one exhaust-port leading therethrough to a point exterior to the casing and another exhaust-port leading through the tail-rod to a point exterior to the

casing and a deflector on the tail-rod for 50 directing the exhaust from the last-named exhaust-port away from the operator.

8. In a hammer-drill, a hammer-cylinder, 55 its tail-rod and a protective casing having its walls entirely spaced from the cylinder, said cylinder having an exhaust-port leading through its side walls to a point exterior to the casing.

9. In a hammer-drill, a hammer-cylinder, 60 its tail-rod and a protective casing having its walls entirely spaced from the cylinder, said cylinder having an exhaust-port leading through the tail-rod to a point exterior to the casing.

10. In a hammer-drill, a hammer-cylinder, 65 its tail-rod and a protective casing having its walls entirely spaced from the cylinder, said cylinder having one exhaust-port leading therethrough to a point exterior to the casing and another exhaust-port leading through 70 the tail-rod to a point exterior to the casing.

11. In a hammer-drill, a hammer-cylinder, 75 its tail-rod, a protective casing having its walls entirely spaced from the cylinder, said cylinder having an exhaust-port leading through its tail-rod to a point exterior to the casing and a deflector on the tail-rod arranged to direct the exhaust away from the operator.

12. In a hammer-drill, a hammer-cylinder, 80 its tail-rod, a protective-casing having its walls entirely spaced from the cylinder, said cylinder having one exhaust-port leading therethrough to a point exterior to the casing and another exhaust-port leading through 85 the tail-rod to a point exterior to the casing and a deflector on the tail-rod for directing the exhaust from the last-named port away from the operator.

In testimony that I claim the foregoing as 90 my invention I have signed my name, in presence of two witnesses, this 5th day of December, 1905.

WILLIAM PRELLWITZ.
